UNITED STATES PATENT OFFICE.

JOSEPH S. LENCKI, OF CHICAGO, ILLINOIS.

METALLIC TIE AND RAIL-FASTENER.

1,216,473.

Specification of Letters Patent. Patented Feb. 20, 1917.

Application filed September 14, 1916. Serial No. 120,120.

To all whom it may concern:

Be it known that I, JOSEPH S. LENCKI, a subject of the Czar of Russia, residing at Chicago, in the county of Cook and State 5 of Illinois, have invented certain new and useful Improvements in Metallic Ties and Rail-Fasteners, of which the following is a specification.

This invention relates to certain new and 10 useful improvements in metallic tie and rail fastener.

The primary object of the invention is the provision of a tie formed of metal provided with a cushioning means for the rails 15 and securing means for locking the rails thereon.

A further object of the invention is the provision of a metallic railway tie that is easy and inexpensive to manufacture, the 20 same being arranged with a rail fastener co-operating therewith whereby a rail may be readily operatively secured thereon.

With these general objects in view and others that will appear as the nature of the 25 invention is better understood, the same consists in the novel construction, combination and arrangement of parts hereinafter more fully described, illustrated in the accompanying drawings, and then claimed.

30 In the drawings forming a part of this application and in which like designating characters refer to corresponding parts throughout the several views:—

Figure 1 is a side elevation of the present 35 device with the rails of a railroad operatively carried thereby.

Fig. 2 is a top plan view of the same.

Fig. 3 is a longitudinal sectional view 40 taken upon line III—III of Fig. 2.

Fig. 4 is an end elevation of the elements shown in Fig. 2.

Fig. 5 is a perspective view of an end portion of the metallic tie.

Fig. 6 is a perspective view of one of the 45 cushioning blocks employed.

Fig. 7 is a perspective view of one of the locking plates.

Fig. 8 is a detail sectional view taken 50 upon line VIII—VIII of Fig. 3, and,

Fig. 9 is a perspective view of a lock nut employed with the rail securing means.

The device contemplates a railway tie 10 of channel-iron formation as best illustrated in Fig. 5 of the drawing open at its top and opposite ends and arranged with spaced transverse partitions 11 adjacent the oppo-

site ends thereof adapted for the reception of a wooden or other resilient block 12 upon which the rails 13 are adapted to be positioned transversely of the tie 10 and secured 60 in position thereon by means of the locking plates 14.

The opposite ends of the tie 10 are similarly formed, being cut-away as at 15 adjacent the sink 16 within which the block 12 65 is positioned and adapted to afford clearance for the rail 13 during the vibrations of the rail when mounted upon the block 12. Mounting posts 17 are provided for the locking plates 14 at opposite sides of the pairs 70 of partitions 11, the said posts being formed integral with the side walls of the tie and the outer pair of posts being preferably arranged in a reinforcing manner at the open end of the tie. The posts are provided with 75 angular notches 18 at the tops thereof within which the locking plates 14 are readily positioned between the sides of the tie 10, spaced upturned fingers 19 being carried by the plates 14 for overlying the base flanges 80 20 of the rail when positioned upon the block 12 within the sink 16 as best illustrated in Fig. 2 of the drawings. An anchoring housing 21 is arranged upon the bottom 22 of the tie 10 adjacent the outer face of each 85 of the partitions 11, each of the said housings having a top wall 23 arranged with a slot 24 adapted for the reception of the shank of a securing bolt 25 having the head 90 26 thereof arranged beneath the top 23 with in the housing, the opposite walls of the latter preventing the bolt from being turned. The bolts 25 project upwardly through perforations 27 in the locking plates 14, lock 95 nuts 28 being arranged upon the upper ends of the said bolts having locking lugs 29 adapted to engage co-operating grooves 30 in the locking plates 14. From this detailed description of the device it will be at once 100 apparent that the rails 13 are secured transversely of the tie 10 by mounting the said rails upon the blocks 12, the latter being positioned within the sink 16. The locking plates 14 are then readily arranged in place 105 and the bolts 25 positioned through the housings 21 and plate perforations 27, the lock nuts 28 being suitably tightened for maintaining the entire structure in its assembled position. It is preferable to form the locking plates 14 of slightly resilient metal to 110 allow the said plates to be adjustably tensioned upon the rail flanges 20 by means of

the lock nuts 28, it being understood that the resilient blocks 12 cushion the rails 13 under the varying strains and conditions and that while the present embodiment of the device 5 is believed to be preferable, minor changes may be made therein without departing from the scope of the appended claims.

What I claim as new is:

1. A metallic railway tie consisting of a channel-shaped member having oppositely-arranged cut-away portions in the upper opposite edges thereof, transverse partitions within the said channel member spaced from the opposite ends of the said cut-away portions, mounting posts oppositely arranged in spaced relations with the outer faces of the said partitions, and hold-fast retaining housings mounted upon the bottom of the said member adjacent the opposite faces of the 20 said partition.
2. A device of the class described comprising a tie of channel shape, transverse spaced partitions arranged between the sides thereof forming sinks therebetween, resilient rail-cushioning blocks arranged within the said sinks, the opposite sides of the said tie having cut-away portions extending beneath the upper faces of the said blocks, posts integrally formed with the opposite sides of the

said tie at opposite sides of the said pairs of partitions arranged with notches in their upper ends, rail-engaging plates seated within the said notches and having fingers overlying the said partitions and blocks when operatively arranged, anchoring housings arranged adjacent the said partitions, and locking bolts for the said plates non-rotatably arranged upright within the said housings.

3. A metallic railway tie and rail fastener 40 comprising a channel-shaped tie having receiving portions adjacent its opposite ends and having its opposite sides cut-away adjacent the said receiving portions, blocks arranged within the said receiving portions, 45 rails positioned upon the said blocks transversely of the said tie within the said cut-away portions, resilient locking plates upon the said tie having spaced fingers overlying the base flanges of the said rails, housings 50 carried by the bottom of the said tie beneath the said plates, locking bolts non-rotatably arranged upright in the said housings projecting through the said plates, and tensioned lock nuts upon the said bolts above 55 the said plates.

In testimony whereof I affix my signature.

JOSEPH S. LENCKI.
